UNITED STATES PATENT OFFICE.

WILLIAM H. SPILLER, OF HOLYOKE, MASSACHUSETTS, ASSIGNOR TO
COBURN TROLLEY TRACK MANUFACTURING COMPANY, OF WIL-
LIMANSETT, MASSACHUSETTS, A CORPORATION.

ELECTRIC SWITCH.

SPECIFICATION forming part of Letters Patent No. 738,952, dated September 15, 1903.

Application filed September 25, 1902. Serial No. 124,799. (No model.)

To all whom it may concern:

Be it known that I, WILLIAM H. SPILLER, a citizen of the United States of America, residing at Holyoke, in the county of Hampden and State of Massachusetts, have invented new and useful Improvements in Electrical Switches, of which the following is a specification.

This invention relates to electrical-switch construction, and has special reference to the construction of an automatic reversing-switch, the object of the invention being to provide a switch of this character whereby, for example, a motor may be automatically reversed by the act of opening and closing the electrical operating-circuit by which the motor is operated. This example is cited, however, only in illustration of one of the many uses to which the switch may be applied. Other uses will readily suggest themselves to one skilled in this art.

In the drawings forming part of this specification, Figure 1 is a front elevation of a switch embodying my invention. Fig. 2 is a sectional elevation of the same, taken substantially through the center thereof. Fig. 3 is a plan view of a bracket on the front of the switch, the contact-posts thereon being shown in section. Fig. 4 is a front elevation showing the parts in a different position to that shown in Fig. 1. Fig. 5 is a plan and rear elevation of a guide-plate on the front of the switch. Fig. 6 is a sectional view on line 6-6, Fig. 4, of a vertically-sliding part on the front of the switch. Fig. 7 is a perspective view from the rear side of a reversing-finger and its support, the parts being represented in separated relations. Fig. 8 is a top plan view of an oscillating frame which carries switch-arms, the manner of connecting the arms together electrically being also shown. Fig. 9 is a diagrammatic view of the electrical circuits of the switch, a source of energy, a motor, and the switch-operating solenoid.

Referring now to the drawings, *a* indicates a metal or other suitable box in which a solenoid *b* is properly secured. The armature or core of the latter is indicated by *c*, and the

two ends of the wire of the solenoid are taken through the casing at any desired point, as at *d*, Fig. 1, and *e* indicates these ends. The lower end of the core *c* is connected by means of a bar *f* with a slide *g*, which is fitted to slide vertically close to the face of the casing, as shown in Figs. 1 and 2, being guided and retained in proper alinement by its engagement with two bosses *h*, planed out to receive it and shown in detail in Fig. 6. Near the upper end of this slide *g* there is pivotally mounted thereon an oscillating adjusting-finger *i*, the lower portion of which is V-shaped, and at the end of the arms of the V are two downturned ears *j*. As the circuit in which the solenoid is included is opened and closed and the core *c* has imparted thereto a vertical movement therewith, the slide *g* moves with it, and upon each downward movement of the slide one of the ears *j* of the oscillating finger *i* engages an abutment alternately on either side of a central vertical line drawn through the axis of said finger, and thus tilts the point of the finger to the right or the left, as the case may be. This movement of the finger *i* is effected as follows: On the front of the casing, near the bottom thereof, there is secured a plate *k*, vertically slotted to permit of its proper adjustment relative to the position of the slide *g* when the latter is at its lowest point. On the back of this plate near the upper end a tappet-finger *m* is pivotally mounted, whose tapered point looks upward and which is supported in this position by a spring *n*, let into a groove in the plate, as shown in Fig. 7, the ends of which spring extend above the upper edge of said plate and bear against opposite sides of said finger *m* to hold its point substantially on the vertical central line of the slide *g*. Preferably the finger *i* oscillates under some slight frictional restraint to the end that after it has been tilted in one direction by contact with the finger *m* it will remain in this position until it is struck on the opposite side of said finger and swung in an opposite direction. However, to insure the retention of the finger *i* in the position to which it is swung by the point *m* a centrally-located guiding-web *o* is ad-

justably secured to the casing at a point just above the end of the finger *i*, to the end that as the latter is swung to one side in the manner described the point of the finger *i* will, 5 as the core *c* enters the solenoid, be restrained by contact with said web *o* from being swung back toward the vertical until the circuit through the solenoid has been broken and the core *c* permitted to drop, whereby the point 10 of the finger *i* will be free to swing under the web *o*. Fig. 5 shows this web and the bracket to which it is secured, there being two views thereof, one in plan and one in side elevation. It is thus apparent that the making 15 and breaking of the circuit in which the solenoid is included will impart to the finger *i* vertical movements, the point of the finger as a result of said movements being inclined and held in a position pointing alternately to 20 the right and to the left upon successive upward movements thereof.

There is hung on the casing at the point *p* a swinging switch-frame *q*, having two parallel arms located at right angles to the face 25 of the box *a*. On each of the arms of the frame *q* are the insulated spring contact-fingers, *r* and *s* on one side and *t* and *u* on the other, each of these fingers being preferably provided at its lower end with a carbon button to prevent sparking, these all being indicated by the letter *v*.

From a point on the frame *q* centrally below the pivotal point thereof the two sides of the lower edge of said frame taper upward, 35 said tapered portions terminating in a notch *w* on each side of the frame for the reception of the point of the adjusting-finger *i*, which in its upward movement will thus swing the frame *q* first to the right and then to the 40 left, bringing the carbon buttons *v* of the contact-fingers *r* and *s* and *t* and *u* alternately into contact with the posts *x* and *y*, which are mounted on a support *z*, extending outwardly from the face of the casing, said posts being 45 insulated from said support. From each side of the frame *q* a spiral spring *q'* extends to some fixed point on the casing and preferably to the binding-posts, (shown in Figs. 1 and 4,) which will be referred to later on. The movements of the frame *q* take place against the 50 tension of these springs, and these may and do herein serve as conductors for carrying the current to the contact-fingers *r* and *s* and *t* and *u* through suitable connections between 55 the latter, which will be described in their proper place.

In the upper end of the solenoid, as shown in Fig. 2, there is located a fixed core *c'*, which is screwed into the upper end of the opening 60 through the solenoid and which is vertically adjustable therein, being retained in its adjusted position by a check-nut *c*². This short core *c'*, when the circuit is closed through the solenoid, becomes an energized armature, 65 which serves to hold the core *c* fixedly in position in the solenoid, within which it would otherwise be subject to fluctuations if through

the manipulation of a rheostat the current passing through the solenoid were varied. This core *c'* closes the end of the passage 70 through the solenoid and the core *c* is made to fit this passage rather snugly, whereby when the solenoid is energized the air between the cores *c* and *c'* will constitute a cushion to prevent the sudden impact of the movable 75 against the fixed core.

Suitable electrical connections extend from a source of power to a motor and from the motor to the above-described switch-operating devices and solenoid, whereby upon the opening 80 and closing of the circuit in which the solenoid is included the above-described parts may be operated to reverse the current through the field of the motor, and thus reverse the rotative movements of the armature thereof, and 85 the construction of these connections will now be described, reference being had to the diagrammatic view shown in Fig. 9 for this purpose. In this figure of the drawings the switch-frame *q* and the fingers *r*, *s*, *t*, and *u* 90 are shown, as in the other drawings, as also are the contact-posts *x* and *y*. The solenoid, however, and motor and source of electricity are shown in diagrammatic form. Referring now to this Fig. 9, 2 may indicate a generator as a source of electricity; 3, the armature of a motor; 4, the field of the latter, and 95 5 any conventional switch or rheostat.

It will be observed, first, that the contact-posts *x* and *y* are the terminals of a circuit 10 (indicated by the numeral 6) which includes the field 4 of the motor. It will also be observed that the spring-finger *t* on one side of the frame *q* which is located opposite one side of the post *y* and the spring-finger *s* on 105 the other arm of the frame which is located opposite one side of the post *x* are connected together by a wire 7, the other two fingers *u* and *r* being similarly connected together by a wire 8. It is thus obvious that if the fingers 110 *r* and *s* are first brought into contact with the posts *x* and *y* and this contact be broken and the fingers *t* and *u* then brought into contact with the other side of these posts any current in either of the wires 7 or 8 would 115 pass through the field 4 in reverse directions. Connection is made with the source 2 directly to the finger *r*, on one side of the frame *q* and opposite the post *y*, and to the finger *t*, on the opposite side of said frame located opposite the other side of said post *y*. These connections consist of the wires 9, running from the source to the armature 3 of the motor, and from the latter the wire is carried to a suitable binding-post 10 and from thence through 120 one of the springs *q'* to the finger *t*, the other side of the connection consisting of a wire 12, running from the source to a binding-post 13, and from thence to the finger *r*, through the other spring *q'*. It is thus seen that the 125 course of the current is from the fingers *r* to *u* and from *t* to *s* and that the movement of the swinging frame *q* will close the circuit 6, causing the current to flow therethrough in 130

one direction, and the swing of the frame *q* to the opposite side will close the circuit 6 in like manner, but the current will flow therethrough in an opposite direction.

5 There remains but one circuit to be described and that is the shunt-circuit through the solenoid, which latter is indicated in the diagram by *b*, which is the same indicating-letter as is used in other figures, although the 10 solenoid is shown only in Fig. 9 in diagrammatic form. This circuit consists in a wire 14, connected to the wire 9 between the armature 3 and the source 2, and running to one side of the switch 5, another wire 15 running 15 from the other side of the switch to one end of the solenoid-coil, and from the opposite end of said coil the wire 15 is carried to and connected with the binding-post 13. This 20 solenoid-circuit, therefore, may be traced as follows: from the source 2 through the wire 9 and the wire 14 to one side of the switch 5; from the opposite side of the switch 5 through the wire 15, and from the solenoid-coil to the binding-post 13, and from thence by the wire 25 12 to the source 2. Thus by manipulating the switch 5 the solenoid may be cut in and out of the circuit which includes the source, as desired, and as the solenoid actuates the 30 swinging frame *q*, whereby the motor-circuit is closed, it is seen that the control of the motor resides in the switch or rheostat 5.

The operation of the device is as follows, assuming the parts to be in the position shown in Fig. 1 and the motor therefor revolving, 35 the circuit 6 being closed: If now the circuit in which the solenoid is included is opened, its core *c* will be released and will drop and with it the slide *g* and the oscillating finger *i* supported thereon.

40 It will be observed by reference to Fig. 1 that the finger *i* is tilted to the right and in its descent to the position shown in Fig. 4 will remain tilted in this direction more or less after the point thereof is in position to swing 45 under the web *o*, and hence the point of the finger *m* will strike on the inclined lower edge of the finger *i* to the right of the apex of its V-shaped lower edge, and coming to a bearing in a notch under the ear *j* will cause the 50 finger to swing over to the left, and if the solenoid-circuit be now closed the upward movement of the core and slide *g* will carry the point of the finger *i* up into the notch *w* of the frame *q*, located to the left of the pivot 55 total point of the latter, and swing the frame on its pivot, causing the contact-points of the arms *r* and *s* to swing against the posts *y* and *x*. Now when the parts are in the position shown in Fig. 1 the contact-points of the arms 60 *t* and *u* lie against the posts *x* and *y*, and hence then the course of the current through the circuit 6 would be as follows: Starting from the source 2, the course of the current will be through the wire 9 and the armature 3 of the 65 motor, for example, to the binding-post 10, thence through the spring *q'* to the arm *t*, in contact with the post *y*, and through this to

the wire 6, thence through the field 4 of the motor back to the post *x*, against which the arm *u* is held through this arm and wire-connection 8 to the line 12, and thence to the source 2. Assuming now that the fingers *t* and *u* are swung away from the contact-posts *x* and *y* and the fingers *r* and *s* swung into contact therewith, then the current passing 75 through the line 9 from the binding-post 10 would pass through the wire connection 7 to the finger *s*, then through the post *x* and circuit 6, traversing the field 4 in a direction opposite to that of the current which enters the 80 field 4 through the contact-post *y*. It is therefore apparent that the current may be sent through the circuit 6 in either direction at will by the interruption of the solenoid-circuit and that a succession of interruptions 85 of this last-named circuit will result in a succession of alternate changes in the direction of the current through the circuit 6, and, as has been stated, while this switch has been shown and described herein in its application 90 to a motor, whereby the direction of rotation of the armature of the latter may be effected, it must be understood that the invention is not confined to its use in this connection, which serves only to illustrate one of its various modes of application. 95

In this application the claims will be confined to the switch proper, in combination with the circuit 6 and a circuit which will include a suitable source of energy and the solenoid. 100 Claims embracing the motor in connection with the switch will be made in another application.

Having thus described my invention, what I claim, and desire to secure by Letters Patent of the United States, is—

1. An electrical switch having two contact-posts which constitute the terminals of a normally open electrical circuit, four movable contact-fingers arranged in pairs, each pair 110 being adapted to swing against said posts alternately; electrical connections between that contact-finger of each pair which contacts with one of the said posts, and the contact-finger of the other pair which contacts with 115 the other post; a second circuit connected with each pair of fingers, a source of electricity in said second circuit, and means for opening and closing the latter.

2. An electrical switch having two contact-posts which constitute the terminals of a normally open circuit, two pairs of contact-fingers mounted to swing against opposite sides of said posts alternately, and cross connections between said posts and said fingers 125 whereby when the pair of fingers on one side of said posts is brought into contact with the latter said normally open circuit will be closed and the current will flow through it in one direction, and whereby when the other pair of contact-fingers is brought into contact with said posts, the current through said circuit will be reversed. 130

3. In an electrical switch, a solenoid, an

electrical circuit in which said solenoid is included, together with a source of electricity and means for opening and closing said circuit; contact-posts in said switch constituting the terminals of a second circuit, two pairs of contact-fingers supported in proximity to the posts, and suitable connections between said fingers and the core of said solenoid whereby the opening and closing of said solenoid-circuit will cause a shifting of the contact-fingers from one position to the other, together with suitable electrical connections between the fingers whereby said alternate contact of each pair of fingers will effect a reversal of the current through said posts.

4. An electrical switch having two contact-posts which constitute the terminals of a normally open circuit, contact-fingers movable against opposite sides of said posts alternately, and cross connections between said posts and said fingers whereby when the fingers on one side of the posts are brought into contact with the latter said normally open circuit will be closed and the current will flow through it in one direction, and whereby when other contact-fingers are moved against said posts the current through the circuit will be reversed.

5. An electrical switch having two contact-posts which constitute the terminals of a normally open circuit, contact-fingers movable against said posts at different times, and cross connections between said posts and said fingers whereby when certain of the fingers are brought into contact with said posts the normally open circuit will be closed and the current will flow therethrough in one direction, and whereby when other of the contact-fingers are moved against said posts the current through said circuit will be reversed.

6. In an electrical switch, separate terminal members included in a normally open working circuit, separate pairs of contacts coöperating with the terminal members, circuit-wire connections between the contacts and also with a source of energy, said connections being so arranged as to reverse the current through the working circuit according to the contacts in action, and an operating-circuit, having a single manual circuit opening and closing device therefor and including a solenoid-controlled means for changing the position of the said contacts.

7. In an electrical switch, separate terminal members included in a normally open working circuit, separate pairs of contacts coöperating with the terminal members, circuit-wire connections between the contacts and also with a source of energy, said connections being so arranged as to reverse the current through the working circuit according to the contacts in action, and an auxiliary circuit in shunt with the circuit including the source of energy, said auxiliary circuit including magnet-controlled operating means for adjusting the position of said contacts.

8. In an electrical switch, a pair of contact-posts constituting the terminals of a normally

open working circuit, a switch-frame having separate pairs of contacts alternately movable to and from the posts, circuit-wire connections between the contacts and also with a source of energy, a solenoid included in an operating-circuit therefor, and an adjusting device carried with the solenoid-core and coacting with the switch-frame to shift the same from one position to the other.

9. In an electrical switch, a pair of contact-posts for the terminals of a normally open working circuit, an oscillatory switch-frame having separate pairs of contacts coöperating with the posts at different times, circuit-wire connections between the contacts and also with a source of energy, a solenoid included in an operating-circuit therefor, an oscillatory adjusting device carried with the solenoid-core and coacting with the switch-frame to shift the same, and a suitably-arranged tappet for shifting the position of the adjusting device.

10. In an electrical switch, a pair of contact-posts for the terminals of a normally open working circuit, an oscillatory switch-frame having separate pairs of contacts coöperating with the posts, a reciprocatory member carried with the solenoid-core, an oscillatory adjusting device carried by said reciprocatory member and engaging with the switch-frame to shift the same, and a suitably-arranged tappet for shifting the position of the adjusting device.

11. In an electrical switch, a pair of contact-posts for the terminals of a working circuit, an oscillatory switch-frame having separate pairs of contacts coöperating with the posts, a reciprocatory member carried with the solenoid-core, an oscillatory adjusting device carried by the reciprocatory member and engaging with the switch-frame during its movement in one direction for shifting such frame, and a tappet arranged in the path of the adjusting device for engagement thereby during its movement in the other direction.

12. In an electrical switch, a pair of contact-posts for the terminals of a working circuit, an oscillatory switch-frame having separate pairs of contacts coöperating with the posts and also provided with oppositely-arranged notched inclines, a reciprocatory slide carried with the solenoid-core, an oscillatory adjusting-finger pivotally mounted upon the slide and having its heel portion provided with shouldered inclines, and a tappet arranged to engage with either of the shouldered inclines of the adjusting-finger in its movement away from the switch-frame.

13. In an electrical switch, a pair of contact-posts for the terminals of a working circuit, an oscillatory switch-frame having a pivotal support and opposite pairs of contact-fingers for engagement with the contact-posts at different times, said switch-frame being further provided with oppositely-arranged notched inclines, a reciprocatory member carried with the solenoid-core, a fixed guide-web, an oscil-

latory adjusting-finger pivotally mounted on the reciprocating member and adapted to be guided at either side of the fixed guide-web in its movement toward the switch-frame, 5 said adjusting-finger having its heel portion provided with shouldered inclines, and a

ranged to engage with either of the shouldered inclines of the adjusting-finger in its movement away from the switch-frame.
